UNITED STATES PATENT OFFICE.

JOHN O. ERSKINE, OF WELLSBURG, WEST VIRGINIA, ASSIGNOR TO JEFFERSON GLASS COMPANY, OF FOLLANSBEE, WEST VIRGINIA.

DESIGN FOR A LAMP-SHADE.

42,319.

Specification for Design.

Patented Mar. 19, 1912.

Application filed September 27, 1911. Serial No. 651,643. Term of patent 7 years.

To all whom it may concern:

Be it known that I, JOHN O. ERSKINE, a citizen of the United States, residing at Wellsburg, in the county of Brooke and State of West Virginia, have invented a new, original, and ornamental Design for Lamp-Shades, of which the following is a specification, reference being had to the accompanying drawing, forming part thereof, in which—

I claim:

The ornamental design for a lamp shade, as shown.

JOHN O. ERSKINE.

Witnesses:

L. O. GRIFFITH,
F. S. TEW.
